UNITED STATES PATENT OFFICE.

ALVA ERNEST CHEESEMAN, OF BRADFORD, PENNSYLVANIA, ASSIGNOR TO THE LEON-
FERENBACH SILK COMPANY, OF WILKES-BARRE, PENNSYLVANIA, A CORPORATION
OF PENNSYLVANIA.

ATTACHMENT FOR SILK-SPINNING MACHINES.

1,223,560.

Specification of Letters Patent. Patented Apr. 24, 1917.

Application filed November 20, 1916. Serial No. 132,428.

To all whom it may concern:

Be it known that I, ALVA ERNEST CHEESEMAN, a citizen of the United States, and resident of Bradford, county of McKean, State of Pennsylvania, have invented certain new and useful Improvements in Attachments for Silk-Spinning Frames, of which the following is a specification.

The present invention relates to improvements in spinning frames and particularly to such frames as are employed in spinning silk.

The object of the invention is to provide means by which in event of breaking the spindle driving belt the feed rolls will be automatically disengaged from the power shaft so that said rolls will not act to draw silk from the bobbins except when the latter are being rotated. In spinning frames of the character to which the improvements relate the bobbin supporting spindles are frictionally driven by the action of an endless belt while the feed rolls are positively driven, and with the constructions heretofore employed when the spindle driving belt breaks the feed rolls continue to draw silk from the bobbins after they have ceased to rotate, thus causing "slack twist."

In the accompanying drawings, the parts of the spinning frame not forming a part of the present invention are shown more or less diagrammatically and not in detail in order that the embodiment of the invention illustrated may be shown on a relatively large scale.

In the drawings,

Figure 1 is a partial elevation and longitudinal section through a silk spinning frame of common construction having the improvements hereinafter described applied thereto;

Fig. 2 is a plan of the parts shown in Fig. 1.

Referring to the drawings, 1, 2, designate respectively the head end stand and rear end stand of a well-known form of silk spinning frame, said stands being connected by longitudinal rails 3 on which are mounted the bobbin supporting spindles 4.

As is usual in machines of the character referred to, the spindles 4 are arranged in two longitudinal series or rows at opposite sides of the machine and are rotated by an endless driving belt 5 which frictionally

bears against said spindles and is held in contact therewith by guide pulleys or rollers 6 arranged at suitable intervals. The belt 5 extends about pulleys 7, 8, the latter being mounted on a main driving shaft 9 supported in bearings on the end frame member 1. 60

A feed roll 10 is arranged above each of the spindles and adapted to rotate a spool 11 in the ordinary manner so that the thread 12 will be drawn from each bobbin 13 mounted on one of the spindles 4 and wound upon the proper spool as the rolls 10 are rotated. The rolls 10 are fast on shafts which extend throughout the length of the frame and beyond the head end stand 1. Each of said shafts is provided with a gear 14. On one of the feed roll supporting shafts is mounted a pinion 15 with which engages a pinion 16 that is supported on a stub shaft so as to be movable longitudinally thereof. Such pinion 16 when in operative position is 75 adapted to connect the pinion 15 with a gear 17 that is geared to the driving shaft 9. However, by means hereinafter described, said pinion 16 may be bodily shifted so that it will not connect the gear 17 and pinion 15 80 and thus disconnect the feed roll shaft from the main driving shaft.

In the embodiment of the invention illustrated, the bodily movable pinion 16 is connected by a suitable yoke 20 with the upper 85 end of a lever 18 that is fulcrumed at an intermediate point of its length on bracket 19 attached to the end frame member 1 and the lower end of said lever is connected with means whereby in event of the spindle driving belt 5 breaking said lever will be rocked about its fulcrum to move the pinion 16 to the right (in Fig. 1) out of engagement with the pinion 15 and gear 17. 90

As previously described and as shown in 95 the drawing, the driving pulley 8 for the spindle driving belt 5 is mounted on the shaft 9 which is fixed in bearings on the end frame 1. The pulley 7 for said belt, however, is mounted on a slide or carriage 21 100 on which is adapted to move in guides 22 on the frame. A suitable spring 23 acting through a lever 24 acts to normally hold the slide or carriage 21 and pulley 7 thereon in such position that the belt 5 is maintained 105 properly taut so that it will rotate the spindles. A rod or link 25 connects the lower end of lever 18 with the slide 21. The

spring 23 is maintained under such strain or tension that if the belt 5 breaks it will act to move the slide 21 farther to the left and this movement will be sufficient to actuate the lever 18 so as to bodily shift the pinion 16 into inoperative position. It will be seen therefore that if the spindle driving belt breaks the shafts driving the feed rolls 10 will be automatically disconnected from the main driving shaft 9 and therefore thread will not be drawn from the bobbins after they have ceased to rotate. As shown, the rod 25 is adjustably connected with an arm 26 extending laterally from the lower end of the lever 18 so that the several parts may be readily adjusted to effect prompt withdrawal of the pinion 16 from operative position when the slide or carriage 21 is moved from its normal position as automatically results when the belt 5 breaks.

Having described the invention what is claimed and desired to be secured by Letters-Patent is,

1. In a spinning frame, the combination of a series of bobbin spindles, an endless belt arranged to rotate the spindles, feed rolls adapted to draw thread from bobbins supported on the spindles, a train of gears for driving the feed rolls including a gear adapted to be bodily shifted toward and from operative position, and means controlled by the spindle driving belt for automatically shifting said gear to inoperative position when said belt breaks, for the purpose described.

2. In a spinning frame, the combination of a series of bobbin spindles, an endless belt arranged to rotate the spindles, a relatively stationary pulley or guide wheel for said belt arranged adjacent one end of the frame,

a second pulley or guide wheel for the belt supported on a slide adjacent the other end of the frame, feed rolls adapted to draw thread from bobbins supported on the spindles, means for positively driving the feed rolls, a spring acting on said slide and guide wheel supported thereby to maintain the spindle driving belt taut and in operative relation to the spindles, and means adapted to be actuated by said spring to automatically render the feed roll driving devices inoperative if the spindle driving belt breaks.

3. In a spinning frame, the combination of a series of bobbin spindles, an endless belt arranged to rotate the spindles, a relatively stationary pulley or guide wheel for said belt arranged adjacent one end of the frame, a second pulley or guide wheel for the belt supported on a slide adjacent the other end of the frame, feed rolls adapted to draw thread from bobbins supported on the spindles, a train of gears for driving the feed rolls, including a gear adapted to be moved bodily to and from operative position, a lever having one arm engaging the slide supporting one of the guide wheels for the bobbin spindle driving belt, a spring acting on the other arm of said lever to maintain said belt in operative relation to the spindles, and a second lever having one arm connected with said bodily movable gear and its other arm connected with said slide, whereby if the spindle driving belt breaks said spring will automatically cause the bodily movable gear to be shifted to inoperative position so that the feed rolls will not draw thread from the bobbins when the latter are not rotating.

In testimony whereof I affix my signature.

ALVA ERNEST CHEESEMAN.
